HYDROEXTRACTOR

Ivanhoe Peter Denysen, Yeadon, and Ross M. Pfalzgraff, Swarthmore, Pa., assignors to American Viscose Corporation, Wilmington, Del., a corporation of Delaware

Application February 14, 1942, Serial No. 430,880

10 Claims. (Cl. 34—58)

This invention relates to an improved construction of hydroextractors, particularly of the type employed in removing excess moisture from wrapped cakes of wound artificial silk yarns by centrifugal force, and is particularly concerned with a novel arrangement for safety and unloading of such hydroextractors.

In the drawing, illustrative of the invention,

Figure 1 shows an elevation of the hydro-extractor with parts thereof in cross-section,

Figure 2 shows an end elevation with parts broken away,

Figure 3 is a side elevation showing an arrangement of a pair of such hydroextractors end to end, and

Figure 4 shows a modified form of candle which may be employed for supporting the cakes in such hydroextractors.

As shown in Figures 1 and 3, a common motor 2 suitably mounted, as by the braces 3 within a central housing 4 supported upon a suitable base or pedestal 5 drives a common shaft 6 which extends from each end of the motor into each of the respective hydroextractors 7, whose housings adjoin that of the motor and may be suitably fastened thereto as by the bolts 8. Alternatively two motors may be used in the housing 4 in place of a single one. Since the hydroextractors are similar in construction, only one will be described in detail.

The extractor housing 9 is provided at the bottom with a drain 10 and two circumferentially extending channels 11 are secured at each end of the housing and have open sides 12 facing each other. The housing is provided with an opening 13 at each side thereof, each such opening being adapted to be closed by a sliding door 14. Each of the two curved edges of the doors may be provided with roller bearings 15 which operate within the channels 11. A pair of chains 16 attached to the uppermost corners of the doors 14 serve to connect them so that opening of one of the doors effects opening of the other. These chains may be provided with rollers 17 for engaging the circular surface of the housing to reduce the frictional resistance to opening and closing of the doors. Each door is provided with a handle 18 to facilitate manipulation. Stops 19 may be provided upon the housing to limit movement of the doors.

A hollow shell rotor 20 is suitably keyed to the shaft 6 for rotation therewith and is provided with a pair of annular ribs 21 and 22 extending outwardly therefrom. These ribs are slotted at regular intervals about their peripheries (as at 23 in Figure 2) to adapt them to receive the

candles 24. Each candle is supported pivotally as at 25 within the slot of the rib 21 and the other rib is provided with a spring latch 26 adjacent to each slot to retain the candle therein. The rotor is further provided with an internal annular gear 27 within its outer end.

The end face of the housing supports a plurality (three being shown) of air-driven pistons 28 fastened by means of the piston rod 29 to an annular plate or guard 30. This annular ring has an internal diameter somewhat larger than the diameter of a circle circumscribed about the ends of the candles which are arranged generally in a circular formation. A suitable flanged stop 31 or a plurality of them may be provided within the interior of the housing to limit the motion of the annular plate 30. Any suitable arrangement of valves or connections may be provided for double-action of the piston, such as the two air pipes 32 and 33, each being connected to one of the closed ends of the cylinder 34 within which the pistons operates.

The end plate of the housing further supports a casing 35 which in turn supports a motor 36 and a cylinder 37 within which a piston 38 operates. The piston is connected by a rod 39 to a shaft 40 upon which are keyed a gear 41 and a pinion 42, the shaft being supported within suitable bearings for axial motion with respect thereto. The motor drives shaft 40 through the pinion 43. An air connection 44 is provided with the cylinder 37 and the piston 38 operates against the resistance of the spring 45 coiled about the rod 39.

35 It is preferable that the shank of the candle 24 be simply a tube or rod having an unbroken cylindrical surface when the machine is arranged with its axis horizontal as shown in Figure 1. However, when vertically arranged, it is preferable to employ the form of candle shown in Figure 1 which is provided with oppositely disposed grooves 46 at regular intervals therealong. Slotted separator plates 47 may be inserted into the respective oppositely disposed grooves between adjacent cakes so that the weight of the cakes does not crush those below.

Figure 4 is a view of a modified form of candle (for use in a vertically arranged machine) as it would appear to one looking up at it as it is disposed in the position of the candle shown in Figure 1. The oppositely disposed grooves 46 in the candle are so arranged as to permit the insertion of cakes of different axial lengths thereon, the separator plates 47 being in those grooves whose spacings correspond to the length of the cakes.

The separators, as shown in this figure, are placed upon this candle in the grooves corresponding to an extra large size cake. Where a cake having about half this length is to be treated separator plates would be placed upon the candle in the positions shown and also in the grooves corresponding to the grooves halfway between. Where an average sized cake is to be treated, the first separator plate from the left end of the candle would be placed in the second pair of grooves and the other plates moved to correspond to the same spacing. In this figure, the candle is represented as a hollow tube having an end plate 48 fastened thereto. The open end is adapted to fit over the pin 49 which is in turn pivoted as by means of 50 within the annular rib 21, in similar fashion to the pivotal head of the candle shown in Figure 1 where such head forms a part of the candle itself.

In operation of the device, the doors are slid open for loading, and loading may proceed from both sides simultaneously or loading may be performed on one side while unloading at the other. Air is introduced to cause engagement of the pinion 42 with the internal gear 27 of the rotor 20 and the motor 36 drives the rotor at slow speeds throughout loading, thereby averting the necessity for the loading and unloading operators to stop the rotor and hold it in any position until that section is loaded. Alternatively, the operation of the motor 36 may be intermittent. One of the other operators may switch the motor 36 on between the loading of one or more candles to bring the next candle into position behind the doors. In this case, high gear reduction between motor 36 and gear 27, acts as a brake to hold the rotor steady while loading.

Where the pivotal head forms part of the candle, as in Figure 1, loading is performed by inserting the cakes and separators, swinging the loaded candle into the slotted rib 22 and latching it in place. Where the type of candle shown in Figure 4 is to be used, loading is performed by placing the cakes and separator plates upon the candle and then inserting the whole candle with its hollow end over the pin 49 pivotally supported upon the annular rib 21, swinging the candle into the corresponding slot of the other rib 22 and latching it in place. After loading, the doors are closed, and air is introduced into cylinders 34 to force the annular plate 30 into the dotted line position of Figure 1 where it prevents damage resulting from the outward swinging of any of the candles in case of failure of or improper functioning of the latches resulting from breakage, release, or improper engagement thereof. The pinion 42 is then released from the internal gear 27 by the spring 45 and the motor 36 is stopped. Thereupon the main motor 2 is started to effect operation of the hydroextractor.

While a preferred embodiment is shown in which the hydroextractors are in a horizontal position, that is, they have their axes horizontal, nevertheless the annular guard plate 30 and the provision for slowly driving the rotor while it is being loaded, may also be applied to the such extractors regardless of the orientation of the rotatory axis. For example, it may also be satisfactorily applied to the extractor when arranged for rotation upon a vertical axis.

While preferred embodiments of the invention have been disclosed, the description is intended to be illustrative only, and it is to be understood that changes and variations may be made with-

out departing from the spirit or scope of the invention as defined by the appended claims.

What we claim is:

1. A centrifugal extractor comprising a rotor, a plurality of supports for wound filamentary material to be extracted spaced about said rotor for rotation therewith, a housing surrounding the supports, an annular guard within the housing, and means for selectively placing said guard into operative position about said supports at one end thereof to prevent damage resulting from outward swinging of said supports and into inoperative position spaced from the supports.
2. A centrifugal extractor comprising a rotor, 15 a plurality of supports for wound filamentary material to be extracted spaced about said rotor for rotation therewith, said supports being pivoted at one end thereof for swinging motion outward with respect to said rotor, means for detachably securing the other ends of the supports to the rotor, a housing surrounding the supports, an annular guard within the housing, and means for placing said guard into and out of position about said other ends of said supports.
3. A centrifugal extractor comprising a rotor, a plurality of pivoted members spaced about said rotor for rotation therewith, supports for wound filamentary material to be extracted each having one end thereof coupled with the corresponding 30 one of said pivoted members, means for detachably securing the other ends of the supports to the rotor, a housing surrounding the supports, an annular guard within the housing, and means for placing said guard into and out of position about said other ends of said supports.
4. A centrifugal extractor comprising a housing, a rotor therein, holders for wound filamentary material pivotally supported on said rotor at one end thereof, doors in said housing permitting access to load and unload said material, an annular guard within said housing, means for placing said guard into and out of position about said holders adjacent their non-pivoted ends, means for driving said rotor at high speed for extraction and auxiliary means for driving said 45 rotor at low speed to facilitate loading and unloading of said material.
5. A centrifugal extractor comprising a housing, 50 a rotor therein disposed on a horizontal axis, holders for wound filamentary material pivotally supported on said rotor at one end thereof, means for driving said rotor at high speed for extraction, a door in the housing adjacent a portion of the arcuate periphery subtended by the holders permitting access to load and unload said material, and auxiliary means for driving said rotor at low speed to facilitate loading and unloading of said material.
6. A centrifugal extractor comprising a housing, 55 a rotor therein, holders for wound filamentary material pivotally supported on said rotor at one end thereof, means for driving said rotor at high speed for extraction, an annular gear secured to the rotor, a pinion, means for moving the pinion into and out of mesh with the annular gear, and an auxiliary motor for driving the pinion.
7. A centrifugal extractor comprising a housing, 60 a rotor therein, holders for wound filamentary material pivotally supported on said rotor at one end thereof, means for driving said rotor at high speed for extraction, an annular gear secured to the rotor, a pinion, means for moving the pinion into and out of mesh with the annular gear, and an auxiliary motor for driving the pinion.
8. A centrifugal extractor comprising a housing, 65 a rotor therein, holders for wound filamentary material pivotally supported on said rotor at one end thereof, means for driving said rotor at high speed for extraction, an annular gear secured to the rotor, a pinion, means for moving the pinion into and out of mesh with the annular gear, and an auxiliary motor for driving the pinion.
9. A centrifugal extractor comprising a housing, 70 a rotor therein, holders for wound filamentary material pivotally supported on said rotor at one end thereof, means for driving said rotor at high speed for extraction, an annular gear secured to the rotor, a pinion, means for moving the pinion into and out of mesh with the annular gear, and an auxiliary motor for driving the pinion.
10. A centrifugal extractor comprising a housing, 75 a rotor therein, holders for wound filamentary material pivotally supported on said rotor at one end thereof, means for driving said rotor at high speed for extraction, an annular gear secured to the rotor, a pinion, means for moving the pinion into and out of mesh with the annular gear, and an auxiliary motor for driving the pinion.

gear, an auxiliary motor and reduction gearing connected thereto for driving the pinion.

8. A centrifugal extractor comprising a housing, a rotor therein, holders for wound filamentary material pivotally supported on said rotor at one end thereof, doors in said housing permitting access to load and unload said material, an annular guard within the housing, means for placing the guard into and out of position about the holders adjacent the non-pivoted ends, means for driving the rotor at high speed for extraction, an annular gear secured to the rotor, a pinion, means for moving the pinion into and out of mesh with the annular gear, an auxiliary motor and reduction gearing connected thereto for driving the pinion.

9. A centrifugal extractor comprising a rotor, a plurality of supports for wound filamentary material to be extracted spaced about said rotor for rotation therewith, means for securing the supports to the rotor for rotation therewith comprising releasable means adjacent a portion of

each support, a housing surrounding the supports, an annular guard within the housing and means for selectively placing said guard into operative position about said supports at one end thereof to prevent damage resulting from outward swinging of said supports and into inoperative position spaced from the supports.

10. A centrifugal extractor comprising a rotor, a plurality of supports for wound filamentary material to be extracted spaced about said rotor for rotation therewith, means for securing the supports to the rotor for rotation therewith comprising releasable means adjacent one end of each support, a housing surrounding the supports, an annular guard within the housing and means for selectively placing said guard into operative position about said supports at one end thereof to prevent damage resulting from outward swinging of said supports and into inoperative position spaced from the supports.
